CLAIM

The ornamental design for an enclosure, as shown and described.

DESCRIPTION

FIG. 1 shows a front perspective view of an enclosure according to a first example embodiment of the present disclosure;

FIG. 2 shows a front elevation view of the enclosure illustrated in FIG. 1;

FIG. 3 shows a rear elevation view of the enclosure illustrated in FIG. 1;

FIG. 4 shows a right side view of the enclosure illustrated in FIG. 1;

FIG. 5 shows a left side view of the enclosure illustrated in FIG. 1;

FIG. 6 shows a top view of the enclosure illustrated in FIG. 1;

FIG. 7 shows a bottom view of the enclosure illustrated in FIG. 1; and,

FIG. 8 shows a rear perspective view of the enclosure illustrated in FIG. 1.

The dashed broken lines show elements or portion thereof that form no part of the claimed design.

1 Claim, 8 Drawing Sheets
